UNITED STATES PATENT OFFICE.

FRANK H. ENSIGN, OF TOLEDO, OHIO.

HUB-CASTING APPARATUS.

SPECIFICATION forming part of Letters Patent No. 376,146, dated January 10, 1888.

Application filed July 28, 1887. Serial No. 245,484. (No model.)

To all whom it may concern:

Be it known that I, FRANK H. ENSIGN, a citizen of the United States, residing at Toledo, in the county of Lucas and State of Ohio, have 5 invented certain new and useful Improvements in Hub-Casting Machines; and I do hereby declare the following to be a full, clear, and exact description of the invention, such as will enable others skilled in the art to which it appertains 10 to make and use the same.

My invention relates to improvements in indestructible molds used for casting the hubs of composite wheels, said molds being preferably made of steel or durable iron, one set 15 serving to cast a large number of hubs. Two of these hubs are ordinarily cast upon one axle, and are located a short space apart in planes transverse and at right angles to the said axle and parallel to each other; but in finishing the 20 said wheel these two sets of spokes, radiating from the two separate hubs, are bent toward each other and their outer extremities are closed into one common rim, for the purpose of forming a bracing-wheel.

25 The first part of my invention consists in mechanism for casting one hub upon an axle; and the second part of my invention consists in the same, with additional mechanism for casting two hubs upon one axle. To accomplish 30 this one section of one of the molds, which is employed in the first operation as an integral half of a mold, must be cut through the plane of its axis into two parts, in order that the said part of the mold may be removed from 35 the axle after the said two hubs have been cast upon the said wheel-axle, all of which will be fully explained hereinafter in describing the operation of these improvements; and the third part of my invention consists in providing 40 molds of a permanent character with suitable indestructible openings for receiving the wheel-spokes (previously formed) and for holding the spokes in position while the molten metal is being introduced into said molds, and 45 also for providing suitable indestructible openings or "sprue-holes" leading into said molds, all the said sprue-holes and openings for spokes being in the same plane of division of said molds, the construction of said mechanism being 50 such that the mouth of said sprue-hole may be elevated above the level of any part of the interior cavities of said molds for receiving

the said molten metal, substantially as hereinafter shown and described. I attain these objects by the mechanism illustrated in the 55 accompanying drawings, in which—

Figure 1 is a vertical section on line A of Fig. 4, showing the molds in a horizontal position and closed. Fig. 2 is a vertical section on the same line A, showing the molds in a 60 vertical position and closed. Fig. 3 is a vertical section on the same line showing the molds open, one lying in a horizontal and one in a vertical position. Fig. 4 is a vertical cross section on line B, Fig. 3, showing the 65 molds open, one lying in a horizontal and one in a vertical position. Fig. 5 is a top view of the apparatus. Fig. 6 is a vertical section of an axle and pair of hubs, one of which hubs is represented as inclosed by its forming-mold. 70

Similar letters refer to similar parts throughout the several views.

Referring to the drawings, C represents the main frame, having the part D, to which is pivoted the swinging arm E, and at the opposite end of the frame C is a post, F, and lugs G near the post F. Between the lugs G, at I, (see Fig. 4,) are pivoted the molds H and H', which molds are adapted to be opened on a substantially longitudinal division, and by 80 means of this pivotal arrangement are adapted to be placed in any of the several positions shown in Figs. 1, 2, and 3. The mold H, by means of the joint J, is also adapted to be opened on the line of a horizontal plane through 85 the center of the pivot J, as shown at K in Fig. 5. This secondary part of the said part H of the mold I have designated in the drawings as H''. The centers of the molds H' and H, which latter part, H, consists of the part 90 H and H'', are cupped out to the proper size and form of the hubs to be cast therein, as shown at L.

In Fig. 6 is represented an axle, M, upon which, at L' and L'', are shown two hubs. 95 The spokes in this view in the hub L'' do not show, on account of their being placed in said hub at different radial angles from those shown in the hub L'. This view is represented as having one of the hubs, L'', inclosed in its forming-molds H and H', for the purpose of elucidating the method of removing the inner mold, H, from the said hub, which will be hereinafter fully explained.

Having described the construction of my invention, its operation is as follows: The molds H and H' are first placed in an open position, as shown in Figs. 3 and 5; but it is not important at this stage of the operation that the mold H should be divided, as shown in Fig. 5. The said molds H and H' having been thus opened, the wrought-iron spokes (which are preferably bent so as to form two spokes from one piece of material) are placed in position, as shown at N in Fig. 5. The mold H is then closed upon the mold H', as shown in Fig. 1, thereby holding the spokes in position, when both molds are raised together to the position shown in Fig. 2, and the axle M is placed in the holes through the centers of the molds. Then, with the mold H preferably bearing against the post F, the two molds H and H' are preferably clamped together by means of a swinging arm, E; but I make no claim to any special device for clamping the molds together, for it is obvious that many well-known devices may be employed for this purpose. The molten metal to form the hub may now be poured into the molds through the sprue-hole O. After the hub so formed has been sufficiently cooled, which cooling is very rapidly performed by means of the conducting and radiating power of metallic chills, the hub and axle are easily removed by dropping the molds H' to the position shown in Fig. 3. After one hub—such as L', for instance—has been thus cast upon an axle, M, the operation of casting a second hub, L", is accomplished in the same manner as that of casting the first hub, L'; but here a difficulty arises, which consists in the removal of the inside mold, H, which, by the cooling of the second hub, L", upon the shaft, has become inclosed between the two hubs L' and L". To accomplish the removal of this mold I divide the said mold on a horizontal plane through its axial line, as shown in Fig. 4, and hinge its parts together, as shown at J. By this means the operation of removing said mold is rendered obvious and easy.

Having described my invention, I do not

claim, broadly, metallic molds for forming or casting wheel-hubs; but

What I claim as new, and desire to secure by Letters Patent, is—

1. The base C, in combination with a two-part mold, the parts of which mold are pivoted together and to the base C, and are adapted to be opened and closed through a substantially longitudinal division, the said mold being provided with a sprue-hole between the said parts and substantially parallel with their line of division, whereby the said mold is adapted to be raised to a vertical position for receiving through said sprue-hole molten metal, and to be lowered to a horizontal position for removal of the casting, substantially as shown and described.

2. The base C, in combination with a two-part mold, the parts of which mold are pivoted together and to the base C, and are adapted to be opened and closed through a substantially horizontal division, the said mold being provided with radial grooves between and substantially parallel with the said division for receiving wheel-spokes N, and with a sprue-hole also between and substantially parallel with the said division, whereby the said mold is adapted to be raised to a vertical position for receiving through said sprue-hole molten metal, and lowered for removal of the casting, substantially as shown and described.

3. The base C, to which are pivoted two parts of a mold whose parts are openable and closable through a substantially longitudinal division, and whose combined parts are adapted to be raised to a vertical position, one of the said parts being subdivided at a substantially right angle to the first-named division, and means for securing the parts of the mold together, substantially as shown and described.

In testimony whereof I affix my signature in presence of two witnesses.

FRANK H. ENSIGN.
